UNITED STATES PATENT OFFICE.

ANTÉNOR ASSORATI, OF PARIS, FRANCE.

PRESS STUD.

Application filed May 31, 1923. Serial No. 642,673.

To all whom it may concern:

Be it known that I, ANTÉNOR ASSORATI, a subject of the King of Italy, and a resident of Paris, Seine, France, have invented certain new and useful Improvements in and Relating to Press Studs, of which the following is a complete specification.

This invention relates to an improved press-stud.

10 In the studs of that kind now in use, the male member of the stud comprises a rounded head which enters the female member and is kept in position by the tension of resilient blades, which engage the male member.

15 The result is that, when the stud is new, if the resilient blades or springs are too strong, it is very difficult to separate the members of the said stud, and the clothes or articles to which the stud is attached are therefore 20 frequently torn. On the other hand, after certain use, the springs deteriorate and are no longer strong enough to keep the stud in its closed position.

25 My present invention intends to remedy these defects, and comprises a female member having an eccentric opening, which opening is arranged to receive the head of the male member, and merge into a recess of smaller width. A spring is provided for 30 keeping the male member in the said recess in order to prevent any direct unintentional removal of the male member, and to enable the opening of said stud to be accomplished by a lateral rather weak conveniently directed pressure upon the said male.

The accompanying drawing shows some embodiments of the stud according to my invention.

35 Fig. 1 represents a side view of the stud, portions of which are shown in section, the members forming the stud being separated.

Fig. 2 represents a top plan view of the female member.

40 Fig. 3 represents a bottom plan view of the same.

Fig. 4 represents a side view of the members in position to coact.

45 Fig. 5 represents a similar view of the members in operation.

50 Fig. 6 represents a modified form of base of the female member having a resilient blade of spiral form.

Fig. 7 represents another form of resilient blade.

55 Fig. 8 represents a modified form of base

of the female member having a different arrangement of slots and resilient blade, and

Fig. 9 represents a modified form of a head for the male member.

The female member of the stud comprises 60 a disc of metal or other suitable material, forming a base 1, which may be secured to an article in any well known or approved manner. The base 1 has a centrally located slot 2 which adjoins an inlet opening 4. 65 This opening 4 is eccentrically disposed in the base and of a size to conveniently admit therethrough the rounded head 3 of the male member.

A resilient blade 5 is fixed to the base 1 70 at the opposite side from that through which the head 3 of the male member enters. This blade 5 is bent so that its free end 6 may move in a slot 7 which adjoins the opening 4 diametrically opposite the slot 2, and is 75 arranged to partially cover the inlet opening 4 in the base. The resilient blade 5 has an opening 8 through which the rounded head 3 of the male member enters and is locked when the members assume a closed or operative position. The free end of the blade 5 is suitably bent, as shown at 9, to prevent, 80 to a certain degree, the unintentional displacement of the male member 3.

The male member 3 is mounted on a disc 85 10 provided with a circular groove 11 which surrounds the head, and is arranged to house the end 6 of the blade 5, when the members are assembled, as in use.

In order to unite the members in coactive 90 relation, the head 3 of the male member is caused to enter the circular opening 4 of the base 1, and engage the bent portion 9 of the resilient blade 5, which will be forced inwardly. When the head 3 has arrived at 95 the bottom of the opening 4, the free end of the blade 5 will exert a lateral pressure upon the rounded head of the male member, thereby causing the latter to slide in the opening 4 toward and into the slot 2. In this position, the slot 2 engages the neck of the male member and locks the members in operative 100 position.

To remove the members from their interlocked engagement, the male member is 105 moved laterally out of the slot, whereupon the head 3 abuts the bent portion 9 of the blade 5 and depresses the same, so that when the head 3 registers with the opening 4 of the base 1, the tension exerted by the 110

blade 5 will cause the head to pass therethrough and be free of the base 1.

The members of the stud may be secured to the article upon which they are to be used by any well known or approved manner. The form of the members may also vary according to the requirements. In the form shown in Fig. 6, the resilient blade 5 is cut from the base 1 in spiral form and has a free end 12 disposed above the opening 4 of the base 1. Abutments 14 are provided on the base 1 to cause the head 3 to register with the opening 4 when moved laterally in the direction to be disengaged from the base 1.

In the form shown in Fig. 7, I provide a resilient blade 13 which is bent into a suitable form and is arranged to move above the opening 4 and allow a lateral pressure sufficient to hold the members in intimate contact.

In the form shown in Fig. 8, the base 1 has a slot 2 and an enlarged opening which is extended laterally therefrom and is of a width in one direction to conveniently receive the head 3 of the male member, and permit the head to move a distance therein, at right angles thereto.

In Fig. 9, I have shown a modified form of head of the male member, which head is rounded to merge into its neck.

What I claim is:

1. A press stud comprising, two members, one of said members being provided with a head and a contracted neck portion, the other member having an opening for the passage of the said head therethrough and a slot adjacent said opening for the reception of the neck portion, and means carried by said last named member arranged to engage the head for yieldingly retaining the neck portion in said slot.

2. A press stud comprising, two members, one of said members being provided with a head and a contracted neck portion, the other member having an opening eccentrically disposed therein for the passage of the said head therethrough and a slot adjacent said opening for the reception of the neck portion, and means carried by said last named member arranged to engage the head for yieldingly retaining the neck portion in said slot.

3. A press stud comprising, two members, one of said members being provided with a head and a contracted neck portion, the other member having an opening eccentrically disposed therein for the passage of the said head therethrough and a centrally arranged slot adjacent said opening for the reception of the neck portion, and means carried by said last named member arranged to engage the head for yieldingly retaining the neck portion in said slot.

4. A press stud comprising, two members,

one of said members being provided with a head and a contracted neck portion, the other member having an opening eccentrically disposed therein for the passage of the said head therethrough and a centrally arranged slot adjacent said opening for the reception of the neck portion, and a resilient blade carried by said last named member arranged to engage the head for yieldingly retaining the neck portion in said slot.

5. A press stud comprising, two members, one of said members being provided with a head and a contracted neck portion, the other member having an opening eccentrically disposed therein for the passage of the said head therethrough and a centrally arranged slot adjacent said opening for the reception of the neck portion, and a resilient blade carried by said last named member arranged to engage the head for yieldingly retaining the neck portion in said slot, the free end of said blade being arranged to register with the opening in the last named member.

6. A press stud comprising, two members, one of said members being provided with a head and a contracted neck portion, the other member having an opening eccentrically disposed therein for the passage of the said head therethrough and a centrally arranged slot adjacent said opening for the reception of the neck portion, and a resilient blade carried by said last named member arranged to engage the head for yieldingly retaining the neck portion in said slot.

7. A press stud comprising, two members, one of said members being provided with a head and a contracted neck portion, the other member having an opening eccentrically disposed therein for the passage of the said head therethrough and a centrally arranged slot adjacent said opening for the reception of the neck portion, and a spirally curved resilient blade carried by said last named member arranged to engage the head for yieldingly retaining the neck portion in said slot.

8. A press stud comprising, two members, one of said members being provided with a head and a contracted neck portion, the other member having an opening eccentrically disposed therein for the passage of the said head therethrough and a centrally arranged slot adjacent said opening for the reception of the neck portion, and a spirally curved resilient blade carried by said last named member arranged to engage the head for yieldingly retaining the neck portion in said slot, the free end of said blade being arranged to register with the opening in the last named member.

9. A press stud comprising, two members, one of said members being provided with a head and a contracted neck portion, the other member having an opening eccentric-

cally disposed therein for the passage of the said head therethrough and a centrally arranged slot adjacent said opening for the reception of the neck portion, and a spirally curved resilient blade formed integrally with said last named member arranged to engage the head for yieldingly retaining the neck portion in said slot.

10. A press stud comprising, two members, one of said members being provided with a head and a contracted neck portion, the other member having an opening eccentrically disposed therein for the passage of the said head therethrough and a centrally

arranged slot adjacently said opening for 15 the reception of the neck portion, and a spirally curved resilient blade formed integrally with said last named member arranged to engage the head for yieldingly retaining the neck portion in said slot, the 20 free end of said blade being arranged to register with the opening in the last named member.

In testimony I have hereunto set my hand at Paris (France) this 15th day of 25 May, 1923.

ANTÉNOR ASSORATI.
